UNITED STATES PATENT OFFICE.

ARTHUR J. FLINT, OF NEW YORK, N. Y., ASSIGNOR TO BRAMBACH PIANO COMPANY, OF NEW YORK, N. Y., A CORPORATION OF NEW YORK.

GRAND-PIANO ACTION.

1,125,084.

Specification of Letters Patent.

Patented Jan. 19, 1915.

Application filed May 28, 1914. Serial No. 841,636.

To all whom it may concern:

Be it known that I, ARTHUR J. FLINT, a citizen of the United States, residing at New York, in the county of New York and State of New York, have invented a new and useful Grand-Piano Action, of which the following is a specification.

This invention relates to a grand piano action and particularly to a sostenuto attachment for such piano action. The sostenuto attachment, so called, is designed to permit the player to hold the dampers raised above one or more strings, thus producing a sustained or singing tone which can be heard above the normally damped notes.

It is the object of my invention to improve the construction of such a device with economy of manufacture and increase efficiency of operation and to provide improved means for conveniently adjusting the several parts of the device.

With this object in view my invention consists in certain devices, arrangements and combinations of parts which will be hereinafter described and more particularly pointed out in the appended claims.

A preferred form of my invention is shown in the drawings in which—

Figure 1 is a partial sectional elevation of a grand piano having my attachment incorporated therein; and Fig. 2 is an enlarged detail view of the attachment.

Referring to the drawings, I have shown the sostenuto attachment as applied to a grand piano action of usual form having strings 10, keys 11, and hammers 12 operated by the usual jacks 13 mounted upon the wippens 14 above the keys 11. Dampers 15 of usual form rest upon the several strings 10 and are connected by rods 16 to collars 17 pivoted at their lower ends to the damper levers 18. All of these parts with the exception of the damper levers may be of any usual form and constitute no part of my invention.

The damper levers 18 are pivotally supported at their rear ends on a flange 19 secured to a fixed rail 20. At its forward end, each damper lever is provided with the usual adjustable cushioned stop 21, positioned above a damper rod 22 pivoted at 23 to the rail 20.

The damper lever 18 is provided with a slot in its lower face within which is re-

ceived a flange projecting upwardly from the sostenuto lever 24, which is pivoted to the damper lever at 25. The lever 24 is provided with a reduced projection 26 upon its forward end, this projection normally extending obliquely downwardly into the path of the sostenuto rod 27. A coil spring 28 is mounted between the rear ends of the levers 18 and 24 and normally tends to force the lever 24 upwardly against an adjusting screw 29 which extends diagonally through the damper lever 18.

The sostenuto rod 27 is pivotally mounted upon the bed of the piano at 30 and is normally positioned as shown in Fig. 1, in which the rod 27 lies outside of the path of movement of the projection 26. Pedal operated connections 31—32 provide means for raising the rod 27 into the path of the projections 26 at the will of the operator.

In order to secure the sostenuto effect, one or more keys are depressed and while thus depressed the sostenuto pedal is operated to move the rod 27 into the position shown in Fig. 2, in which position it prevents the descent of the damper levers and dampers when the keys are released. The sostenuto levers which were not raised before the rod 27 was operated will remain in the position indicated at 26^a in Fig. 2, the projections 26^a extending beneath the rod 27. If it is desired to operate the keys associated with any one of these levers the operation is permitted by the yielding connection between the damper levers 18 and the sostenuto levers 24.

Having thus described my invention it will be evident that many changes and modifications can be made therein by those skilled in the art without departing from the spirit and scope of my invention as set forth in the claims and I do not wish to be limited to the specific details herein disclosed but

What I do claim is:

1. In a grand piano action, in combination, a damper lever, a sostenuto lever pivoted thereto and depending therefrom, a spring normally forcing the operative end of said sostenuto lever upwardly, an adjustable stop for limiting the upward movement of said lever, and a pedal-operated bar movable into the path of the operative end of the sostenuto lever.
2. In a grand piano action, in combination, a damper lever having a slot in its

under side, a sostenuto lever having a flange extending into said slot and pivoted to said damper lever, said sostenuto lever having a reduced projection extending obliquely downwardly, a bar movable into the path of said projection, and pedal-operated means to move said bar.

3. In a grand piano action, in combination, a damper lever, a sostenuto lever pivoted thereto, said lever having a reduced projection extending obliquely downwardly,

a spring normally forcing the operative end of said lever upwardly, and an adjustable stop limiting the upward movement of said lever.

In testimony whereof I have hereunto set my hand, in the presence of two subscribing witnesses.

ARTHUR J. FLINT.
